KEY HOLDER

James M. Collins, North Attleboro, Mass.

Application April 11, 1935, Serial No. 15,850

5 Claims.

(Cl. 59—96)

This invention relates to an improved key-holder or key-ring adapted for attachment to a chain or the like or to be carried in the pocket or other receptacle.

One object of the invention is to provide a key-holder or key-ring of the type indicated which maintains the keys suspended in close association and compact arrangement so that they may be conveniently carried in the pocket or other receptacle without bulging or expanding the same.

Another object of the invention is to provide an improved key-ring or key-holder having means for securely locking the keys in connected relationship therewith while permitting their ready removal and replacement.

Another object of the invention is to provide an improved key-ring or key-holder in which the key-retaining means may be easily manipulated to release the keys while being securely held closed and locked in position.

Another object of the invention is to provide a device of the type indicated which is of simple structure, economical to manufacture and more convenient in use than previously known articles of like nature.

Further objects of the improvement are set forth in the following specification which describes the improved key-ring or key-holder in several different forms as illustrated by the accompanying drawing. In the drawing:

Fig. 1 is a perspective view showing a preferred form of the improved key-ring or key-holder with a chain attached thereto and a plurality of keys suspended therefrom;

Fig. 2 is an enlarged side view of this form of key-ring showing the latch or retaining-means swung into open position to permit placing the keys on or removing them from the ring;

Fig. 3 is an enlarged detailed sectional view, taken on line 3—3 of Fig. 2, showing the construction of the swivel ring for attachment to the chain;

Fig. 4 is a view similar to Fig. 2 showing a modified form of construction of the device; and

Fig. 5 is a perspective view of the latch and suspension means for this type of device.

The present invention consists in general in providing a U-shaped or bifurcated loop-member adapted to be passed through the openings in the keys with the legs or free ends of the loop connected by a latching device and having a swiveled suspension member for joinder to the end of a chain.

In Figs. 1 and 2 the bifurcated loop-member 2 is illustrated as constructed from a strip of spring metal of rectangular cross-section which is bent into a semi-circular loop 3 with legs 4 and 5 extending therefrom. One of the legs 4 is bent at right-angles to form a lateral end-portion or

arm 6 projecting to a point substantially midway between the ends of the legs. The end of the arm 6 is formed with a hub or enlargement 7 pierced with a hole for receiving a pin or rivet 8 which serves as a pivot for a latch-member 10. The latch-member 10 is constructed in the form of a relatively narrow loop having opposite parallel arms with bosses 11 at their ends adapted to straddle the sides of the boss or hub 7 on the end of the arm 6. The bosses 11 are provided with apertures for receiving the ends of the pin or rivet 8 which is headed over to pivotally connect the parts in the manner as later explained.

The free end of the arm 5 is beveled at 12 and formed on its outer side with a detent-notch or recess 13 adapted to receive the looped end of the latch 10 when the leg 5 is sprung toward the leg 4 to close the ring in the manner illustrated in Fig. 1 of the drawing. The beveled end 12 of the leg 5 facilitates the sliding of the loop of the latch 10 over the end of the leg and when it engages in the detent-notch 13 a secure connection is effected.

In its preferred form the improved key-ring is provided with means for attaching it to a cord or chain and, as shown in Fig. 3, such means comprises a bifurcated member 15 arranged with its legs straddling the sides of the bosses 11 on the latch 10 and pivotally connected to the hub 7 on the arm 6 of the ring by the rivet 8. Referring further to Fig. 3, the connecting cross-piece 17 of the element 15 is provided with a hole for receiving the shank 18 of a ring 20 for attachment to the end of a chain 21 shown in Fig. 1. For this purpose the chain 21 preferably has a so-called "jump-ring" which may be hooked through the swivel-ring 20 and closed by means of a spring-latch 22. The shank 18 of the ring 20 has its end headed over at 23 to secure it to the bifurcated element 15, this connection being made loosely to allow the ring to turn freely on a vertical axis, as viewed in Fig. 3, while the pivot joint of the element 15 allows the whole to swing on a horizontal axis; thus providing a completely swiveled connection between the key-ring and the chain.

Fig. 4 illustrates a modified form of the device wherein the bifurcated member or loop 24 is constructed of round wire instead of wire of rectangular cross-section as shown in Figs. 1 and 2. In this embodiment of the invention the latching-means is of slightly different form, comprising a loop-like member 25 having bosses 26 at the ends of its arms pivotally connected to a hub 27 at the end of the cross-arm 28 on the bifurcated member 24 by means of a rivet or pin 29. Formed integral with the latch 25 is a secondary loop 30 extending from the bosses 26 at substantially right-angles to the first loop. The loop 30 has a rounded portion for connection with a ring at 60

the end of a key-chain and also serves as a handle or finger-piece for swinging the latch 25 to engage its end with, or release it from, the notch 31 in the end of the free leg 32 of the bifurcated member 24.

With either form of construction the method of operation of the device is as next explained. When it is desired to place one or a number of keys on the ring or holder the leg 5 is sprung 10 toward the opposite leg 4 to release the end of the latch 10 from the notch 13 so that the latch may be swung upwardly to the position illustrated in Fig. 2. When the latch 10 is released in this manner the leg 5 springs outwardly away 15 from the leg 4, thereby providing a relatively wide opening to permit the keys to be readily placed over the end of the leg 5 to adapt them to assume a grouped relationship as shown in Fig. 1.

When the desired number of keys have been 20 placed on the holder in the manner as above described the leg 5 is sprung inwardly toward the leg 4 and the latch 10 swung downwardly to engage its end in the detent-notch 13. In this way the ring or holder is closed with its two legs securely connected or locked together to prevent the keys from being accidentally released therefrom. The holder with its attached keys may be carried loosely in the pocket, bag or other receptacle or may be attached to a chain 21 in the 25 manner shown in Fig. 1. The swiveled connection of the ring 20 with the end of the cross-arm 6 of the holder provides for free movement of the holder to adapt it to assume a convenient position when selecting a particular key to be used or when the holder with its attached keys 30 is placed in the pocket or other receptacle.

Due to the inherent spring tendency of the wire or other material from which the holder is constructed the latch 10 is securely held in locking engagement with the end of the leg 5 of the loop-member 2 to resist any tendency to unlatch or open the holder. The keys may slide around the loop-member 2 and in one position will bring up against the cross-arm 6; while if 45 sliding in the opposite direction they will be held by the latch 10 so that they cannot possibly escape from the ring.

The method of operation of the modified form of construction shown in Fig. 4 is essentially the 50 same as that of the construction first described, except that the latch 25 may be conveniently manipulated by pressure of the fingers on its looped portion 30, the dash lines in Fig. 4 indicating the latch-member as adjusted to open 55 position.

It will be observed from the foregoing that the present invention provides a particularly simple and ingenious form of key-ring or holder which may be manufactured from strip material 60 in the nature of round or square wire by a simple bending operation. The latch-member may be struck up from sheet-metal and the parts joined by a simple riveting operation. Where the swiveled ring connection is employed this 65 may also be constructed from stampings so that the whole device is designed to be manufactured at low cost. At the same time, the device is extremely practical in use and safe and secure as a holder for keys or the like.

It is to be understood that modifications other than those herein shown may be made in the structure and arrangement of the parts of the device without departing from the spirit or scope of the invention. Therefore, without limiting 75 myself in this respect, I claim:

1. A key-holder comprising a loop-member constructed of resilient material and having a curved portion and parallel legs extending from the ends of its curved portion with a cross-arm projecting inwardly from the end of one of the legs, a loop-shaped latch pivoted to the end of said cross-arm to adapt it to be swung into engagement with the free end of the opposite leg of the loop, said opposite leg being provided with means at its end for locking engagement with the 10 looped end of the latch, and supporting means for the loop member connected to the cross arm medially of the parallel legs. 5

2. A key-holder comprising a U-shaped loop-member formed of resilient strip material and 15 having parallel extending legs adapted to be flexed toward and away from each other, one of said legs being bent at right-angles to form an inwardly-directed lateral arm and the opposite leg provided with a detent-notch at its end, a 20 loop-shaped latch pivoted to the end of the lateral arm medially of the parallel legs and shaped to adapt its closed end to slide over the end of the free leg when the latter is resiliently flexed toward the opposite leg to engage the notch there- 25 in, a swivel member hinged to the pivot for the latch, and a ring swivelly connected to said member.

3. A key-holder comprising a bifurcated member 30 constructed from resilient strip-material bent into an arcuate loop with opposite parallel legs forming continuations thereof, the end of one of the legs being provided with a detent-notch and the opposite leg being bent at right-angles to form a laterally extending cross-arm having an 35 apertured hub at its end, a latch constructed in the form of a loop having its sides straddling the hub on the cross-arm and pivoted thereto medially of the parallel legs with its closed end adapted to slide over the end of the free leg of the bifurcated member to engage the detent-notch there- 40 in, and supporting means for the bifurcated member hinged to the pivot for the latch. 50

4. A key-holder comprising a bifurcated member 45 of resilient strip material having a curved portion with opposite parallel legs extending therefrom, one of said legs formed with a detent-notch at its end and the opposite leg being bent at substantially right-angles to form a laterally-extending cross-arm, and a latch member in the 50 form of a double loop having its sides pivoted to the end of the cross-arm medially of the parallel legs with one looped end of the latch adapted to slide over the end of the free leg of the bifurcated member to snap into the notch therein and the 55 other loop portion disposed to extend upwardly from the pivot to provide a connection for a chain or the like.

5. A key-holder comprising a bifurcated member 60 constructed of resilient strip material bent into the form of a loop having parallel legs extending therefrom, one of said legs being beveled at its end and provided with a notch disposed inwardly therefrom, the opposite leg being bent at right-angles to form a laterally-extending 65 cross-arm, a latch of bifurcated form pivoted to the end of the cross-arm medially of the parallel legs with its looped end adapted to engage the beveled end of the free leg to resiliently flex the latter toward the opposite leg and slide thereover 70 to snap into engagement with the detent-notch to lock the latch in closed position, and a closed loop hinged to the pivot for the latch. 75
